Sweden, assignors to Svenska Aktiebolaget
Gasaccumulator, Stockholm, Sweden, a corpora-
tion of Sweden

Application March 21, 1934, Serial No. 716,555
In Sweden December 13, 1933

7 Claims. (CL 158—5)

The present invention relates to control for liquid fuel combustion apparatus. More particularly, the invention relates to control for liquid fuel combustion apparatus of the kind in which liquid fuel is vaporized due to heat generated by the combustion apparatus and thereafter burned in its vaporized or gaseous state.

Still more particularly, the invention relates to the control of the liquid fuel supply to combustion apparatus of the vaporizing type in which vaporized fuel is continuously supplied to a burner from a plurality of liquid fuel vaporizers which are operated alternatively with individual vaporizers in intermittent operation.

The invention is particularly applicable to fuel combustion apparatus for devices such as domestic cook stoves of the heat accumulating type which require continuous burner operation and will be hereinafter described in its application to a domestic cook stove of the above character. It is to be understood, however, that the invention is not limited to cook stoves, nor is it limited in its application to fuel combustion apparatus of the specific kind illustrated by way of example.

Amongst the several objects of the invention are; to provide novel and improved means for shutting off the supply of fuel to a burner of the vaporizing type in the event proper vaporization of the fuel ceases; to provide, in combination with such means, fuel regulating means for maintaining a desired constant temperature of a part or parts heated by heat from the burner; and to provide safety and control means as above stated for liquid fuel combustion apparatus of the vaporizing type in which vaporization of the fuel is effected by intermittent and alternative operation of a plurality of fuel vaporizers.

Further and more detailed objects, together with the specific nature of the invention and the advantages to be derived from its use, may best be understood from a consideration of the following description of one suitable form of apparatus for carrying the invention into effect.

In the accompanying drawings, forming part of this specification:

Fig. 1 is a vertical section of a domestic cook stove to which apparatus embodying the invention is applied, taken on the line 1—1 of Fig. 5;

Fig. 2 is a similar section on an enlarged scale showing part of the apparatus illustrated in Fig. 1;

Fig. 3 is a section taken on the line 3—3 of Fig. 2;

Fig. 4 is a section taken on the line 4—4 of Fig. 2;

Fig. 5 is a section on an enlarged scale taken on the lines 5—5 of Figs. 1 and 2; and

Fig. 6 is a view taken on the line 6—6 of Fig. 2.

Referring now to Figs. 1 and 2, the stove indicated generally at A is of the type adapted to be continuously maintained at elevated temperature and comprises a relatively heavy metal structure indicated generally at 10 and providing hot plates 12 and 14 and an oven 16. A second low temperature oven 18 may also be provided. The hot plates 12 and 14 and also oven 16 are adapted to be heated by conduction of heat through the metal from gases of combustion which pass through channel 20 to a suitable stack opening 22 adapted to be connected to the chimney. The metal structure 10 is adapted to accumulate heat and is surrounded by suitable insulating material, such as asbestos or kieselguhr, indicated at 24, and the hot plates 12 and 14 are covered when not in use by insulated cover plates 26 and 28.

The hot combustion gases for heating the structure 10 are provided by a burner indicated generally at 30 and adapted to burn a gaseous fuel mixture comprising air and hydrocarbon fuel vapor. Air for combustion is supplied to burner

30 through the passage 32 which is in communication with the surrounding atmosphere through the opening 34. Around the base of the burner 30 there is provided a metal mass 36 having two vaporizing chambers 38 and 40 therein (see Figs. 3 and 4). Chambers 38 and 40 are each placed in communication with the lower portion of the burner 30 by means of passage 42 and the ports 44 and 46. Chamber 38 has associated therewith a liquid fuel feeding member 48, the lower portion of which provides a central fuel feeding tip

50 from which liquid fuel is adapted to fall onto a vaporizing surface 52, which in this instance is provided by the bottom wall of the vaporizing chamber. The vaporizing chamber and the lower part of the fuel feeding member are connected by means of a pipe 54 and an annular space 56 communicating with pipe 54 surrounds the fuel feeding tip of the member 48. Chamber 40 has associated therewith a like fuel feeding member 58 having a fuel feeding tip 60 adapted to cause fuel to fall onto the vaporizing surface 62. Chamber 40 and member 58 are connected by pipe 64 and tip 60 is surrounded by annular space 66.

Fuel is supplied alternatively to one or the other of the fuel feeding members by apparatus which will now be described. Liquid hydrocarbon fuel is fed, preferably by gravity, from a suitable reservoir (not shown) through the supply line 68 (Fig. 5) through a strainer 70 in a chamber 72,

from which it flows through the passage 74 to a float chamber 76 in which the level of fluid is maintained substantially constant by the float 78, which operates to control flow of fuel through the passage 74. From the float chamber 76 fuel flows through the pipe 80, the labyrinth 82 and pipe 84 to a feeding orifice 86 controlled by a needle valve 88. The orifice 86 is positioned above a cup-shaped receptacle 90 in which is pivotally mounted a plate 92 adapted to direct fuel either to the outlet passage 94 leading from chamber 98 in receptacle 90, or to the outlet passage 96 leading from chamber 100 therein. Chambers 98 and 100 are separated by the web 102. Passages 94 and 96 communicate respectively with the fuel feeding members 58 and 48, the connection between passage 94 and fuel feeding member 58 being shown in Fig. 2 and comprising an inclined conduit 104. The fuel feeding members 48 and 58 and the receptacle 90 are preferably formed by a single integral casting, as shown in Fig. 2, through which the several fuel feeding passages are bored.

The annular spaces 56 and 66 surrounding the tips of each of the fuel feeding members are placed in communication with the surrounding atmosphere to permit a restricted amount of air to be admitted at these places for a purpose to be explained later. In Fig. 2 the connection for this air supply to the fuel feeding member 58 is shown at 106.

The vaporizing chambers 38 and 40 and the lower portion of the burner are in communication with the overflow pipe 108, the outer end of this pipe terminating in a discharge opening 110 (Fig. 5), beneath which there is suspended an overflow receptacle 112. Receptacle 112 is suspended from a spring bar or strip 114, to which is attached stem 116 of the needle valve 88. As shown in Fig. 5, the needle valve 88 is preferably made adjustable with respect to the strip 114 by means of suitable adjusting nuts. The end of the strip 114 opposite that from which the receptacle 112 is supported is fixed to the free end of a hollow curved expansion element 120 of the Bourdon tube type. The opposite end of the expansion element 120 is connected by means of a tube 128 to a thermostat element 129 such as that shown at 129 in Fig. 1, which is placed in a position such that it will be responsive to the temperature of any desired part receiving heat from the burner. Tube 128 and elements 129 and 120 are adapted to be filled with any suitable expansible thermostat fluid. The position of the end of the element 120 to which the tube 128 is attached, is determined by the position of lever 124, which is pivoted at 126 and is provided with an arm 122 bearing against or attached to the element 120 so as to cause movement of this element upon movement of the lever 124. The position of lever 124 is determined by the position of a cam 134 mounted on a shaft or spindle 135, which is advantageously carried to the exterior of the stove. Lever 124 is held in contact with cam 134 by the action of a spring 130 working against any suitable fixed abutment such as that indicated at 132. Intermediate the end of the spring strip 114, to which the element 120 is attached, and the place of attachment of the stem 116 of the needle valve 88, there is attached an adjustable stop 118, the position of which with respect to the strip may be adjusted by means of suitable adjusting nuts, and which is adapted in certain positions of the

strip to bear against a fixed abutment, such, for example, as the top of the casing forming the chamber 72, as will hereinafter be explained.

The position of the plate 92 for directing fuel either to passage 94 or to passage 96 is controlled by means of an arm 136 projecting upwardly from the plate and at its upper end engaging the bifurcated lower end 138 of a lever 140 pivoted at 142. The upper arm of lever 140 is bent so as to project through an arcuate slot 144 in the outer casing 146 of the stove, and terminates in an indicator arm 148 having an actuating handle 150. The outer casing 146 of the stove preferably has marked thereon the scale or index 1—15, 15—1, as indicated in Fig. 6.

The metal mass 36 is preferably enclosed in insulating material indicated at 152, and air passing to the air supply pipe 32 of the burner also advantageously circulates in the space 154 around the insulation 152 and also around the fuel feeding members and the parts providing the channels for supplying fuel and air to these members.

While the form of fuel burner employed constitutes per se no part of the present invention, the burner arrangement shown herein by way of example, which forms the claimed subject matter of my copending application Serial No. 695,883, filed October 30, 1933, is of advantageous form. In this burner arrangement the metal mass 36 provides a cup-shaped space with the bottom of which passage 42 is in communication, and in the center of which there is disposed the perforated burner pipe 156. A second and larger perforated burner pipe 158, the lower end of which is above the lower end of pipe 156, surrounds pipe 156 to provide between the two pipes an annular space 160. A third pipe 162, larger in diameter than pipe 158 and imperforate, surrounds pipe 158. The lower end of pipe 162 is above the lower end of pipe 158. The space 160 between pipes 156 and 158 is in communication with the pipe 164, which serves to place the burner in communication with the combustion gas channel in the structure 10.

The operation is as follows:

Fuel vapor is burned in the space 160 by combustion air admitted thereto through perforated pipes 156 and 158, both of which pipes are in communication with the air space 154. The heat of combustion heats the mass 36 to high temperature, a high temperature of this mass being readily maintained because of the fact that the mass is well insulated, and by conduction through the metal the vaporizing surfaces 52 and 62 are maintained at very high temperature, for example, 900° F. or higher. Liquid fuel drops or falls through the orifice 86 onto the plate 92 and flows through the associated fuel conduit to one of the fuel feeding members. From the tip of the fuel feeding member the fuel falls onto the hot vaporizing surface and is substantially instantaneously vaporized. The vapor formed in the vaporizing chamber is drawn by the draft created by the burner through the passage 42 to the space between the two perforated burner pipes. Due to the suction created by the burner shaft, air is drawn through the pipes (one of which is shown at 106 in Fig. 2) to the spaces around the fuel feeding tips 50 and 60 of the two fuel feeding members, this admission of air being continuous with respect to both of the fuel feeding members since both of the vaporizing chambers are in uninterrupted communication with the

burner and therefore are continuously subject to draft from the burner whenever the burner is in operation. The quantity of air admitted around the fuel feeding orifice is restricted, being insufficient in amount to form a combustible gas mixture with the fuel vapors being formed in the vaporizing chamber to which fuel is being admitted. As will be evident, the air admitted through a pipe such as pipe 108 will be relatively cool as compared with the temperature of the mass 36 and the parts associated therewith, and the purpose of this air supply is to enshroud the falling fuel so as to prevent premature vaporization thereof. By so enshrouding the falling fuel and conducting it to the fuel feeding member through passages which are relatively cool, the formation of carbon deposits at or adjacent to the fuel feeding member due either to premature vaporization or recondensation of fuel vapors on the wall surfaces is materially retarded if not entirely eliminated, and the formation of a carbonaceous deposit of a coke-like nature on the vaporizing surface is also retarded because of the fact that the oxygen content of the restricted quantity of air, while insufficient to form a combustible gas mixture in the vaporizing chamber, will tend to burn away such carbonaceous deposit as it forms. Due to the introduction of this restricted air supply to the vaporizing chamber, the accumulation of carbonaceous deposits of fuel residue in the chamber is very slow, but in time sufficient accumulation may occur to adversely effect the efficient operation of the vaporizer, particularly when a substantial accumulation of residue or coke forms on the vaporizing surface.

In order to permit the continuous operation of the burner for long periods without interruption, and also in order to effect removal of carbonaceous accumulations from the vaporizers, a plurality of vaporizers is provided and after one vaporizer has been in operation for a period of time, which experience has indicated will result in the accumulation of an undesirable amount of residue in the vaporizing chamber, the supply of fuel to such vaporizer is cut off, and fuel is directed to another vaporizing chamber. It will be evident that in a construction such as that disclosed, fuel vapor will be substantially immediately formed in the vaporizing chamber to which fuel has been directed, so that there will be no interruption in the supply of fuel vapor to the burner. Even if there were sufficient interruption in the supply of fuel vapor to cause the burner flame to be extinguished, the entire apparatus is at such high temperature that ignition would automatically occur immediately upon the resumption of the supplying of fuel vapor. The restricted supply of air admitted to the vaporizing chamber from which fuel has been cut off continues to flow through this chamber under the influence of the burner draft, and because of the fact that the vaporizing chamber is continuously maintained at very high temperature, the oxygen in the air continuing to flow to the vaporizing chamber combines with the carbonaceous residue therein and gradually burns away the deposits in the chamber while another vaporizing chamber is in operation.

With a fuel vaporizing arrangement of the kind shown, the formation of carbonaceous deposits in the vaporizing chambers is so slow that continuous operation of the burner may readily be effected with but two vaporizing chambers adapted to be operated in alternation. Experience has shown that where the apparatus is utilized in

connection with the heating of a cook stove of the type illustrated, vaporization of the required amount of fuel may be effected continuously by a single vaporizer for a period of about a month, but it is preferable to change operation of the vaporizers somewhat more frequently, and in order to insure the shifting of operation of the vaporizers at proper intervals, the index indicated in Fig. 6 is advantageously employed in conjunction with the shifting lever 148. This index is advantageously marked 1-15 and 15-1, the figures representing the days of a month, it being intended that the shifting lever 148 be in the position shown in Fig. 6 during the period from the first to the fifteenth day of a given month, and in the opposite position during the period from the fifteenth of a given month to the first of the succeeding month.

With fuel combustion apparatus of the vaporizing type such, for example, as that hereinbefore described, it will be evident that serious difficulty and even danger may arise if for any reason vaporization of the liquid fuel fed to the apparatus ceases, since in such event the apparatus is subject to flooding and overflow of liquid fuel. In order to prevent any possibility of this occurring, we have, in accordance with the present invention, provided the overflow vessel 112 acting on the needle valve 88, the position of which is also under the influence of the thermostat, the action of which is as follows: when the part which is in heat conducting relation with the thermostat element 129 is relatively cold, the pressure of the expansible thermostat fluid in the expansion element 120 is low, and this element contracts so as to lift the end of the spring strip 114 to which the needle valve 88 is attached, thus providing for increased flow of fuel from the orifice 86. As the temperature of the parts heated by the burner increase the pressure of the thermostatic fluid increases in the element 120, and due to the expansion of this element under pressure, tending to straighten the element in the manner common to all Bourdon tubes the needle valve 88 is depressed, and the supply of fuel flowing over orifice 86 is decreased until a stabilized condition is arrived at with only sufficient fuel being supplied to maintain the parts heated by the burner at the desired temperature. The adjusting means on the valve stem 116 are ordinarily employed only for initial adjustment when setting up the apparatus, and adjustment of the thermostat to vary the temperature at which equilibrium is established by the thermostat is effected by adjustment of cam 134. It will be evident that if the cam 134 is moved in clock-wise direction, as from the position shown in Fig. 5, the lever 124 will be moved in counter-clock-wise direction about the pivot 126, and the element 120 will be turned so as to effect an increase in the amount of fuel supplied through the needle valve 88.

If for any reason, vaporization of the liquid fuel supplied to either of the vaporizing chambers ceases to occur at its proper rate, the excess unvaporized liquid fuel will accumulate and flow through pipe 108 to the receptacle 112 and the increased weight of the receptacle will pull the end of the spring strip 114 downwardly to close the valve 88 regardless of the fact that failure to vaporize the fuel will be accompanied by decrease in burner temperature and consequent action by the thermostat control tending to open valve 88. Adjustment of the amount of weight required to effect closure of valve 88 is effected by means of

adjusting the position of the stop 118. When this stop is not in contact with a fixed abutment the receptacle 112 is supported by a lever the length of which is the full length of the part 114, but when the part 114 is pulled downwardly to a position such that the stop 118 comes in contact with a fixed abutment, the length of the lever is shortened, and its resistance to bending, due to the weight of the receptacle 112, increases. Consequently, by adjusting the position of the stop 118, the weight of liquid in the receptacle 112 necessary to effect closure of the needle valve may be readily fixed at any predetermined value.

By the above described arrangement, effective safety and control apparatus is provided which is very simple and reliable in operation. Also, by means of apparatus of the kind disclosed, it is possible to secure effective regulation and also safety of operation with vaporizing apparatus of the kind in which a plurality of separate vaporizers are employed. As previously stated, however, it is to be distinctly understood that in its broader aspects the present invention is not limited to combustion apparatus for any specific use, nor is it in its broader aspects to be limited to liquid fuel combustion apparatus of the specific kind hereinbefore described by way of example. The invention is capable of embodiment in many different specific forms of apparatus, and is accordingly to be understood as including all such forms of apparatus as may fall within the scope of the appended claims.

What we claim is:

1. Apparatus of the character described comprising a device adapted to be maintained at elevated temperature due to the heat of gases of combustion, a burner adapted to burn a gaseous fuel mixture for supplying heat to said device, a vaporizer adapted to vaporize liquid fuel for combustion in the burner, a supply conduit for supplying liquid fuel to the vaporizer, a control valve in said conduit having a movable valve member, a curved tube expandible upon increase in the temperature of said device, a spring element fixed to the free end of said tube said movable valve member being mounted on said spring element to move toward closed position upon expansion of said tube, and an overflow vessel for receiving unvaporized liquid fuel from the vaporizer suspended from said spring element to close said valve in the event of fluid fuel overflow.

2. In apparatus of the character described, a liquid fuel vaporizer for supplying gaseous fuel vapor to a burner, a curved tubular thermostat element having a fixed end and a free end, said element being expandible in response to increase in heat supplied by the burner, a spring element secured at one end to the free end of said tubular element, a supply conduit for supplying liquid fuel to the vaporizer, a control valve in said conduit having a movable valve member secured to said spring element so as to be moved toward closed position by expansion of said tubular element, means for adjusting the position of said tubular element, and means actuated by the weight of unvaporized liquid fuel overflowing from said vaporizer and acting on said spring member for closing said valve.

3. In apparatus of the character described, a liquid fuel vaporizer for supplying gaseous fuel vapor to a burner, a curved tubular thermostat element having a fixed end and a free end, said element being expandible in response to increase in heat supplied by the burner, a spring element secured at one end to the free end of said ele-

ment, a supply conduit for supplying liquid fuel to the vaporizer, a control valve in said conduit having a movable valve member secured to said spring element so as to be moved toward closed position by expansion of said tubular element, means for adjusting the position of said tubular element, an overflow vessel suspended from said spring element for closing said valve due to overflow of unvaporized liquid fuel from the vaporizer to said vessel a fixed abutment, and adjustable means associated with said spring element and contacting said fixed abutment in certain positions of the spring element for determining the weight of liquid fuel in said overflow vessel required to effect closure of the valve.

4. Apparatus of the character described comprising a device to be maintained at elevated temperature due to the heat of gases of combustion, a burner for burning a gaseous fuel mixture for supplying heat to said device, a plurality of liquid fuel vaporizers for supplying fuel vapor to said burner, each of said vaporizers comprising a vaporizing chamber and a vaporizing surface arranged to be heated from said burner to a temperature sufficient to vaporize liquid fuel, fuel feeding members for causing liquid fuel to fall on said vaporizing surfaces, passages providing uninterrupted communication between said vaporizing chambers and said burner, means for supplying fuel alternatively to different fuel feeding members including a common fuel supply conduit, a control valve in said conduit, and a thermostat for regulating said valve in response to variations in the heat requirements of said device.

5. Apparatus of the character described comprising a device to be maintained continuously at elevated temperature due to heat of gases of combustion, a burner for burning a gaseous fuel mixture for supplying heat to said device, a plurality of liquid fuel vaporizers for supplying fuel vapor to said burner, each of said vaporizers comprising a vaporizing chamber and a vaporizing surface arranged to be heated from said burner to a temperature sufficient to vaporize liquid fuel, fuel feeding members for causing liquid fuel to fall on said vaporizing surfaces, passages providing uninterrupted communication between said vaporizing chambers and said burner, means for supplying fuel alternatively to different fuel feeding members including a common fuel supply conduit, a control valve in said conduit, and means responsive to overflow of unvaporized liquid fuel from any one of said vaporizing chambers for closing said valve.

6. Apparatus of the character described comprising a device to be maintained continuously at elevated temperature due to the heat of gases of combustion, a burner for burning a gaseous fuel mixture for supplying heat to said device, a plurality of liquid fuel vaporizers for supplying fuel vapor to said burner, each of said vaporizers comprising a vaporizing chamber and a vaporizing surface arranged to be heated from said burner to a temperature sufficient to vaporize liquid fuel, fuel feeding members for causing liquid fuel to fall on said vaporizing surfaces, passages providing uninterrupted communication between said vaporizing chambers and said burner, means for supplying fuel alternatively to different fuel feeding members including a common fuel supply conduit, a control valve in said conduit, means for regulating said valve in response to variations in the heat requirements of said device, and means responsive to overflow of unvaporized

liquid fuel from any one of said vaporizing chambers for closing said valve.

7. Apparatus of the character described comprising a device to be maintained continuously at elevated temperature due to heat of gases of combustion, a burner for burning a gaseous fuel mixture for supplying heat to said device, a plurality of liquid fuel vaporizers for supplying fuel vapor to said burner, each of said vaporizers comprising a vaporizing chamber and a vaporizing surface arranged to be heated from said burner to a temperature sufficient to vaporize liquid fuel, fuel feeding members for causing liquid fuel to

fall on said vaporizing surfaces, passages providing uninterrupted communication between said vaporizing chambers and said burner, means for supplying fuel alternatively to different fuel feeding members including a common fuel supply conduit, a control valve in said conduit, thermostat means for regulating the position of said valve in response to variations in the heat requirements of the device, and manually operable means for adjusting said thermostat means. 10

GUSTAF DALÉN.
